UNITED STATES PATENT OFFICE.

LEON GSCHWIND, OF YOUNGSTOWN, OHIO.

IRONING MACHINE

Application filed March 18, 1921. Serial No. 453,856.

To all whom it may concern:

Be it known that I, LEON GSCHWIND, a resident of Youngstown, in the county of Mahoning and State of Ohio, a citizen of the United States, have invented certain new and useful Improvements in Ironing Machines, of which the following is a specification.

My invention relates to improvements in ironing machines and refers particularly to a type of machine best suited for ironing flat work, although it may be used for any character of ironing where it would operate in an efficient and practical manner.

One object of my invention is the provision of an ironing machine which may be operated by any kind of motive power and which will be under easy control of a single operator or tender.

Another object of my invention is the provision of an ironing machine which will be of simple, durable and compact construction to occupy a small amount of space and which being composed of comparatively few parts will withstand hard usage without damage or getting out of order.

Another object of my invention is the provision of an ironing machine operated by any character of power and in connection with any desired heating means and which will handle a large amount of work in a rapid and efficient manner, and thus generally from every point of view insure a desirable, efficient and practical machine.

To attain the object stated and such others as are inherent in a machine of this character, my invention consists of an ironing machine embodying novel features of construction and combination of parts for service substantially as shown, described and particularly defined by the claims, it being of course understood that any changes may be made in the invention which fall within the scope of the claims.

The construction in detail and the operation of my machine will be fully understood from the accompanying drawings and its features of merit and advantages will be appreciated by reference to said drawings, in which:

Figure 1 represents an end elevation of an ironing machine constructed in accordance with and embodying my invention, the parts which comprise the machine being in the position they occupy when the machine is in operation.

Fig. 2 represents a similar view, the parts being in the position they assume when the machine has been thrown out of operation.

Fig. 3 represents a front elevation of the machine looking in the direction of the work or feeding table of the machine.

Fig. 4 represents an end elevation with the parts in operating position and showing particularly the driving mechanism for the ironing roller and the clutch used in connection with said driving mechanism.

Fig. 5 represents a central sectional view of the hollow ironing roller and a part of connected mechanism, and

Fig. 6 represents a plan view of the ironing roller as well as the driving and clutch mechanism.

Fig. 7 represents a detail view on an enlarged scale showing a preferred form of electric motor driving mechanism for the ironing roller, and

Fig. 8 represents a sectional view thereof.

Referring by numeral to the drawings in which the same numbers of reference are employed to designate the same parts in all the views:

The numeral 1 designates the pair of frame members, connected by rods or cross members 2, and having intermediately supported therebetween on cleats or brackets 3, the work receiving member 4, while the upper portion of the frame members are provided with the pairs of arms 5, which as will presently appear, provided means for supporting the ironing roller and ironing head or member.

Mounted upon the lower rearward rod 2 at its inner end 6, is the pedal lever 7, formed with the foot pedal 8 and connected to said lever at 9 is the lower end of the link 10, whose upper end is connected at 11 to the shaft 12, upon which is mounted the inner end of the pair of arms 13, whose outer ends 14 are connected to the pair of levers 15 with which it is pivoted at 16 and to the extremities of the levers and the frame are secured the springs 17, said pair of levers 15 being fulcrumed at 18 to one of the pair of arms 5 of the frame, while to the upper ends of said pair of levers are pivoted at 19, the lugs 20 on the hollow pressing or ironing member or head 21, provided with the curved or arcuate ironing surface 22, said hollow ironing member being supplied with heat through the inlet 23, as will be readily understood.

On a cross bar 26 that connects the two sides of the frame on which is adapted to swing a lever comprising the arms 25 and 27 the latter being pivoted at 12 to the link 14 while the end 27 is adjustably secured to the links 30 by means of the bolts 28 that pass through the slots 29 and are clamped at any desired point to provide for the pressure and movement of the pressing head 21.

10 The links 30 carry at their upper ends the feed table 32 that has at its front edge the bar or handle 33 by which the table is moved, and said feed table is pivoted at 35 to the swinging supports 34 that are journaled to a bar 36 extending across the frame.

15 The relations of the pivots 31 and 35 are such that as the table is pulled outward by the handle 33 it will substantially follow the rounded surface of the roller.

20 This movement of the table also elevates the treadle 8, as clearly illustrated in Figs. 1 and 2 but it is obvious that pressure on the treadle in Fig. 2 will restore the above mentioned parts to the position shown in Fig. 1.

25 The hollow ironing roller 37, which in use may be covered with felt or suitable fabric is mounted between the arms 5 of the frame and may be supplied with heat through the pipe 38, or may be furnished with heat in any desired manner to its hollow interior, and at one end is formed with the hub 39, upon which is mounted the gear wheel 40, which wheel meshes with the worm gear 41, mounted on the shaft 42, carrying a pulley 43, which receives a driving belt operated from any desired source and said shaft is mounted in a pair of brackets 44, secured rigidly to the frame, 30 while upon said shaft is mounted the sliding clutch member 45, operated by means of the yoke 46, the rod 47 and the roller 48, which is engaged by one of the pair of arms 30 to move said rod 47 and yoke 46, to permit engagement of the clutch member 45, with the clutch collar 49 formed on the worm 41. In Fig. 4 the clutch and its connections are shown in the position they occupy when the parts are in engagement. 40 The sliding yoke is moved to cause engagement of the clutch elements by means of the coiled spring 50, while movement of the arms 30 when the ironing element 21 is thrown out of engagement with the roll 37 45 slides the yoke and connected clutch member away from said clutch collar 49 against the action of the spring 50 and causes the driving mechanism to be disengaged.

50 The construction just described is the form of mechanism used when the driving source is remote from the machine proper, while in Figs. 7 and 8 I show a form of electric motor driven mechanism which forms a part of the machine and which is considered the 55 most desirable means of driving the ironing

roller, and in said mechanism the gear wheel 51 on the ironing roller supporting shaft 52, engages the small gear wheel 53, which is mounted on the stub shaft 54 and which shaft also carries the large worm driving gear 55, which is in mesh with the worm 56, upon the shaft 57 of the electric motor 58, which mechanism is all mounted at one end of the frame of the machine and while having ample power to rotate the ironing roller is of small and compact construction to add little to the size of the machine.

60 The operation of my machine will be readily understood from the foregoing description taken in connection with the drawings and it is not thought necessary to enlarge thereon, but reference to Fig. 1 shows that depression of the foot pedal moves the connected arms and angle levers to cause the ironing head and work table to be brought into close proximity with the ironing roller, while in Fig. 2 elevation of said foot pedal moves the pair of arms and angle levers to cause retreat of the ironing head and feed table out of operative position, the machine when in operation receiving the flat work from the feed table carrying it under the ironing head and when the ironing has been completed permitting the work to fall into the receiving tray or member 4.

65 The advantages of my machine will be instantly apparent to any person skilled in such structures and it will be evident that the machine will prove efficient, desirable and practical in every important particular.

70 I claim:—

75 1. An ironing machine of the character described, consisting of a frame, an ironing roller mounted in said frame, a work table and ironing head having a swinging connection with said frame and with reference to the ironing roller, and means for swinging said work table and ironing head into and out of operative position, said means consisting of a pair of levers fulcrumed to the frame and having one end pivoted to the ironing head, a pair of arms connected to said levers, a pair of angle levers connected to said arms and fulcrumed upon the frame, 80 swinging supports depending from the work table and connected with said angle levers, and a foot pedal connected to the inner ends of said arms and angle levers.

85 2. In an ironing machine, the combination of a roller, driving means for the same, a clutch in the driving means, a pressing head at one side of the roller, a feed table at the other side of the roller, means operated by the feed table to open the clutch and raise the pressing head from the roller, and a treadle adapted to restore the pressing head and raise the feed table to cause the latter to permit the clutch to close.

90 3. In an ironing machine, the combination of a roller, driving gear embracing a clutch,

a presser head adapted to engage the roller, arms carrying the head, a feed table, swinging arms connected with the feed table, an arm connected with one of the clutch members and adapted to be engaged and moved by one of the swinging arms of the feed table, levers and links adapted to be expanded and force the pressing head against

the roller, means carried by the feed table to break the levers and links, and a treadle 10 and link adapted to expand the said levers, and links.

In testimony whereof I hereunto affix my signature.

LEON GSCHWIND.
